UNITED STATES PATENT OFFICE.

LEONARD KUNDINGER, OF SEBEWAING, MICHIGAN.

BEAN-SEPARATOR.

1,371,313.

Specification of Letters Patent. Patented Mar. 15, 1921.

Application filed October 7, 1918. Serial No. 257,160.

To all whom it may concern:

Be it known that I, LEONARD KUNDINGER, a citizen of the United States, residing at Sebewaing, in the county of Huron and State of Michigan, have invented certain new and useful Improvements in Bean-Separators, of which the following is a specification.

This invention relates to improvements in bean separators and its object primarily is the separation of bad beans and other waste material from good beans. A further object is to provide a device of this type that will accomplish the maximum amount of work with the minimum of effort on the part of the operator or attendant. A further object is to provide a simple compact machine of this type that is efficient in operation and cheap to manufacture. With the foregoing and other objects in view the invention consists in the combination and arrangement of parts to be hereinafter fully described, pointed out in the appended claim and illustrated in the accompanying drawings which form a part of this specification and in which—

Figure 1 is a view of my improved bean separator in side elevation, partly broken out to afford a better illustration.

Fig. 2 is an enlarged fragmentary sectional view of the force feed mechanism.

Fig. 3 is a top plan view of the device.

Fig. 4 is an end view of Fig. 1.

Like reference characters denote corresponding parts throughout the several views.

My separator comprises a frame comprising the supporting legs 1 connected by the base bars 2, 3 and carrying the top bars 4 to which the auxiliary end frame 5 is secured that supports the hopper 6 the semi-cylindrical pit 7 of which is formed with an opening 8 which may be closed by a sliding gate 9 having an elongated slot 10 therein through which a pin 11 extends that is carried by the pit 7, said pin slidably securing the said gate to the pit 7. A cord 12 secured to one end of the gate 9 is attached to a thumb screw 13 carried by the hopper which thumb screw, as it is turned in one direction, will serve to slide the gate 9 into open position. Within the hopper pit 7 is a longitudinally grooved feed roller 14 fast upon a shaft 15 which is journaled in the ends of the pit 7 and which carries upon one end a pulley 16 which is connected by belt 17 with the pulleys 18, 19, the former of which is

arranged upon a pin-shaft 20 carried at one end of a lever 21 fulcrumed upon a pin 22 carried by the hopper 6, the opposite end of said lever being connected by a contractile spring 23 to the hopper, said lever, spring and pulley 18 serving as adjusting and tightening means for the belt 17. The said pulley 19 is fast upon the conveyer shaft 24 which is journaled in the ends of the top bars 4, said conveyer shaft carrying a roller 24^a and one end of the conveyer 25, the other end of which is carried by the shaft 26 which carries roller 26^a and which is journaled in the bearings 27 carried upon the adjusting screws 28 which move through bearings 29 carried by the frame and which screws are actuated and controlled by the nuts 30. It is obvious that by means of the supports of shaft 26 that shaft may be moved toward or away from the shaft 24 to regulate the tension of the conveyer 25.

Upon the said shaft 24 a large wheel 31 is made fast which is connected by belt 32 to a small pulley 33 fast upon the double crank shaft 34, said belt 32 passing over the guide pulleys 35, 36, the former of which is carried at the end of a bar 37 fulcrumed upon one of the cross bars 39 of the frame, said bar 37 being yieldingly pressed downward by the spring 40 arranged upon a bolt 41, said bolt connecting the bar 37 and cross bar 39. The said shaft 34 is journaled in a bearing 42 that connects two of the legs 1 and in a standard 43 carried by the framework, said shaft carrying a fly wheel 44, said shaft 34, further, being connected by the pitmen 45, 46 to the pedals 47, 48 which are operatively connected to the foot board 49 carried by the frame. To the top bars 4 I secure a pair of adjustable guide arms 50 which extend inwardly over the conveyer 25 and are retained in adjusted position by means of a pair of spring arms 51, and another pair of adjustable guide arms 52 spaced away from the arms 50 and operatively carried by a bar 53 secured to a shelf 54 connecting the top bars 4 at one end of the machine, said shelf being spaced away from the conveyer.

Secured to the top bars 4 and lying outside the same are the wings 55 formed with the recesses 56 and to said wings the arm rests 57 are secured by the hinges 58. Beneath the canvas conveyer 25 and secured to the frame are the chutes 59, 60 which are so positioned as to register with the recesses

56 in the said wings 55, said chutes 59, 60 opening into the spout 61 and another chute 62 also disposed beneath the conveyer 25 registers with the opening 63 formed between the conveyer and the shelf 54. In operation the beans are deposited in the hopper 6 and from the pit 7 thereof they are forced by the feed roller 14 out through the opening 8 upon the conveyer 25. The guide 10 arms 50 serve to prevent the beans from spreading laterally and falling off the conveyer which latter member carries them forward or longitudinally of the frame, the operator easily preventing them from becoming choked between the free ends of said 15 arms. Such beans as may move off the conveyer laterally between the arms 50 and 52 will drop through the recessed portion 56 of wings 55 into the chutes 59, 60 and out 20 through spout 61 unto such containers as may be provided for them. Most of the beans will pass from the arms 50 between the arms 52 and will be conducted to the end of the conveyer and deposited through 25 the opening 63 formed between said conveyer and shelf 54 into the chute 62 and from the same into such receptacle as may

be provided to receive them. The force feed device provided in the hopper pit insures a more even distribution of the beans over the 30 conveyer and the pairs of arms arranged immediately above the conveyer relieve the operator of the trouble previously experienced of seeking to prevent the beans from working off the conveyer laterally as the arms 35 tend to keep the beans together making them easier to pick and sort.

What is claimed is:—

In a bean separator, a frame, a conveyer mounted in said frame, and two pairs of 40 arms pivotally carried by said frame immediately above said conveyer, said arms being spaced away from each other in pairs, one pair of arms being straight arms and the other pair being of angular formation and 45 receiving the beans from the straight arms.

In testimony that I claim the foregoing as my own I have hereto affixed my signature in the presence of two subscribing witnesses.

LEONARD KUNDINGER.
